US0D1020734S

(12) **United States Design Patent** (10) **Patent No.:** **US D1,020,734 S**
(45) **Date of Patent:** **** Apr. 2, 2024**

(54) **LAPTOP COMPUTER**

(71) Applicant: **Lenovo (Beijing) Limited**, Beijing (CN)

(72) Inventor: **Jen-Ting Wei**, Beijing (CN)

(73) Assignee: **Lenovo (Beijing) Limited**, Beijing (CN)

(**) Term: **15 Years**

(21) Appl. No.: **35/515,911**

(22) Filed: **Nov. 23, 2022**

(80) **Hague Agreement Data**

Int. Filing Date: **Nov. 23, 2022**

Int. Reg. No.: **DM/225687**

Int. Reg. Date: **Nov. 23, 2022**

Int. Reg. Pub. Date: **Dec. 30, 2022**

(30) **Foreign Application Priority Data**

May 23, 2022 (CN) 202230306481.4

(51) **LOC (14) Cl.** **14-02**

(52) **U.S. Cl.**

USPC **D14/327**; D14/315; D14/440

(58) **Field of Classification Search**

USPC ..... D14/336, 432, 448, 439, 440, 443, 447, D14/203.1, 203.7, 331, 315-327, 333, (Continued)

CLAIM

The ornamental design for a laptop computer, as shown and described.

DESCRIPTION

1.1 : Front view

1.2 : Back view

1.3 : Left view

1.4 : Right view

1.5 : Top view

1.6 : Bottom view

1.7 : Perspective view

1.8 : Front view of unfolding state

1.9 : Back view of unfolding state

1.10 : Left view of unfolding state

1.11 : Right view of unfolding state

1.12 : Top view of unfolding state

1.13 : Bottom view of unfolding state

1.14 : Front perspective view of unfolding state

1.15 : Back perspective view of unfolding state

1.16 : Enlarged view

2.1 : Front view

2.2 : Back view

2.3 : Left view

2.4 : Right view

2.5 : Top view

2.6 : Bottom view

2.7 : Perspective view

2.8 : Front view of unfolding state

2.9 : Back view of unfolding state

2.10 : Left view of unfolding state

2.11 : Right view of unfolding state

2.12 : Top view of unfolding state

2.13 : Bottom view of unfolding state

2.14 : Front perspective view of unfolding state

2.15 : Back perspective view of unfolding state

(Continued)

2.16 : Enlarged view	1/1669; G06F 1/1671; G06F 1/1675; G06F 1/1681; G06F 1/1686; G06F
3.1 : Front view	1/1688; G06F 1/169; G06F 1/1692; G06F
3.2 : Back view	1/181; H05K 5/0017; H05K 5/03; H05K
3.3 : Left view	5/0052; H05K 5/0069; H05K 5/0217; H05K 5/0239; H05K 5/0249; H05K
3.4 : Right view	5/0247; H05K 5/003; H04B 1/3888; H04M 1/0202; H04M 1/021; H04M
3.5 : Top view	1/0212; H04M 1/0279; H04M 1/0281; H04M 1/0283
3.6 : Bottom view	
3.7 : Perspective view	
3.8 : Front view of unfolding state	
3.9 : Back view of unfolding state
